BOOKHOLDER

John E. Newberg, Chicago, Ill.

Application January 25, 1929. Serial No. 334,872

4 Claims. (Cl. 45—90)

This invention relates to book holders and more particularly to a device of that character to be applied as an attachment to a desk for holding, within convenient reach of the user, telephone directories or similar reference books.

In large cities, telephone directories have become quite voluminous, and, in fact, have so increased in size as to necessitate in some cases, separating the regular alphabetical listing of 10 subscribers and the business classifications into separate volumes, and, in addition thereto, a special suburban book is sometimes published. Obviously, these volumes are quite cumbersome and take up considerable room as well as being 15 unsightly on top of a desk.

The present invention has for its principal object to provide a simple yet practical structure which may be applied to the desk in such a way that the book-holding portion thereof is normally 20 supported out of sight, but within convenient reach, and having provision whereby the user may readily move said book-holding portion on its support to a position where the book may be easily removed from and replaced on the 25 holder, at will.

Other objects and advantages to be attained will appear in the following description.

The invention consists in the parts and combinations and arrangements of parts herein- 30 after described and pointed out with particularity in the appended claims.

In the accompanying drawings forming a part of this specification and illustrating practical adaptations of the invention,

35 Fig. 1 is a transverse section through an ordinary flat-top desk showing the book holder in retracted position;

Fig. 2 is a front elevation thereof;

40 Fig. 3 is a transverse section of another desk structure, on an enlarged scale, showing a modification of the means for attaching the book-holding device to the desk;

Fig. 4 is a fragmentary front elevation of the desk and attachment shown in Fig. 3;

45 Fig. 5 is an inverted plan view of the supporting trackway; and

Fig. 6 is a top plan view of the reciprocatory carrier and the book holder thereon.

50 Referring now to the drawings, the numeral 10 designates the ordinary flat-top desk which, as shown, is supported at its ends by the usual pedestal frames 11 in which are located the drawers 12. In other respects the desk is of the usual structure and is provided with the other regular conveniences, such as the center drawer

13, and slidable leaves 14, and the like. However, the details of the desk structure, as to the foregoing features, form no particular part of the present invention and the same are merely referred to incidentally.

The device of the present invention includes a 60 channeled trackway, preferably of sheet metal, the same comprising a main body portion 15, right angular side walls 16, and inturned marginal flanges 17 whose meeting edges are spaced 65 apart, thereby affording a longitudinal slot 18.

Slidably longitudinally in the trackway 15 is a carriage 19 comprising a rectangular main body plate, from the center of which depends a longitudinal flange or rib 20, to which latter the 70 book holder 21 is attached.

Preferably, the book holder 21 is constructed of sheet metal, the outer shell being conveniently formed from a single sheet constituting the bottom, side, end and top walls, the meeting marginal portions of the sheet, after forming the top wall, being flanged as at 22 and secured on opposite sides of said depending flange or rib 20 of the carriage 19, either by riveting the same as at 23, spot-welding, or by any other 80 approved method of attachment.

The forward portion of the carriage 19 is supported by rollers 24 which are mounted on the under sides of the marginal flanges 17 of 85 said trackway and extend upwardly through slots 25 provided therefor in said flanges. The said carriage 19 is provided at its rear portion with a pair of rollers 26 which are located in slots 27 provided therefor, said rollers 26 projecting on opposite sides of said carriage 19 so 90 as to ride in contact with either the central body portion of the trackway 15 or its marginal flanges 17, as will now be described; said rollers 26, for the purpose, being of a diameter slightly less than the distance between said portion 15 95 of the trackway and its marginal flanges 17.

Normally, in the retracted position of the device, as shown in Figs. 1 and 3 of the drawings, the forward portion of the carriage 19 is supported on the rollers 24, while the rear end 100 portion thereof is supported by the rollers 26 which are at this time resting on the flanges 17 of the trackway. When the device is moved forwardly from this normal position it rides for a time in the supported relation just above described, but as soon as it has moved a distance sufficient to shift its preponderance of weight 105 forwardly beyond the axes of the rollers 24, naturally, the carriage 19 tends to tilt about said axes, thereby throwing the rear end por- 110

tion of the carriage upwardly whereupon the rollers 26 ride in contact with the central body portion of the trackway. Obviously, therefore, the device is easily moved longitudinally of its supporting trackway.

The trackway 15 may be attached to the desk in various ways, according to the structure of the desk. As shown in Fig. 1, the desk is provided with a cross piece 28 near its front, and 10 the trackway, therefore, is conveniently attached to the under side of said cross piece, while the rear portion of the trackway is attached to the portion 29 of the desk frame.

In the modification illustrated in Figs. 3 and 15 4, wherein the cross piece 28 and frame member 29 are omitted from the desk structure, angle brackets 30 are secured to the side panel 31 of the end supporting pedestal 11 of the desk, as at 32, by screws or bolts. To the under sides 20 of the horizontal legs 33 of said brackets 30, the trackway 15 is riveted, as at 34, or it may be otherwise secured thereto according to any approved or desirable practice.

The book holder 21 may be divided into any 25 desirable number of compartments by providing the partitions 35, of which there are two illustrated in the drawings, thereby producing three compartments 36, 37 and 38, respectively. As shown, these compartments are open at the 30 front, and it is preferable to incline the bottom wall 41 and correspondingly incline the rear wall 42 thereof, said bottom and rear walls being disposed substantially at right angles to each other. By this arrangement the books are not 35 so liable to be jolted out of the holder when reciprocating the carriage on the trackway. For convenience in withdrawing the carriage it is provided with a recess 39 on its under side, or it may obviously be provided with a suitable 40 hand pull in lieu of said recess. So, too, a stop, such as the angle member 40, may be provided to limit the inward position of the book holder.

From the foregoing it is apparent that a device 45 is produced which is normally located out of the way of the user of the desk, yet it is conveniently withdrawable so as to have easy access to the books contained in the holder 21, at will.

While the structures illustrated in the drawings 50 embody practical adaptations of the invention, it is to be understood that there may be many minor changes and modifications made

and substituted without departing from the spirit and scope of the invention as defined by the appended claims.

Having described my invention, what I claim as new and desire to secure by Letters Patent is: 80

1. In a device of the character described, a supporting trackway comprising a channeled member having parallel marginal flanges spaced apart, a carriage comprising a rectangular body plate, said body plate having bearing rollers at its rear end portions between the body of said trackway and its said marginal flanges, said carriage having a depending longitudinal rib projected through the space between the marginal flanges of said trackway, a book holder mounted on said longitudinally ribbed portion of said carriage, and bearing rollers on said marginal flanges of said trackway for supporting the forward portion of said carriage. 85

2. The herein described book holder comprising a channeled trackway, said trackway having spaced parallel marginal flanges, said flanges having bearing rollers at the forward end portions thereof, a carriage comprising a rectangular body plate normally supported at its forward portion of said bearing rollers of said trackway, and having bearing rollers at its rear end portions cooperating with the body portion of said trackway and the marginal flanges thereof, said body portion of the carriage having a depending longitudinal rib projected through the space between said marginal flanges of said trackway, and a block holder depending from said longitudinally ribbed portion of the carriage, said book holder having a book-receiving compartment open at its front and being provided with substantially right angularly disposed inclined bottom and rear walls. 95

3. In a desk provided with the usual leg-clearance space, a carriage on said trackway, a book holder mounted upon and movable with said carriage upon said trackway by means of bearing rollers. 100

4. In a desk with the usual leg clearance space thereunder, a trackway located therein to one side of said clearance space so as not to interfere with the legs of the user, means movable on said trackway for supporting a book holder, 105 and a book holder supported by said means. 110
